UNITED STATES PATENT OFFICE.

HARRY ARTHUR FOOTHORAP, OF HARRISBURG, PENNSYLVANIA, ASSIGNOR TO ELLIOTT-FISHER COMPANY, A CORPORATION OF DELAWARE.

DATE-PRINTING MECHANISM FOR WRITING ADDING MACHINES.

Application filed December 31, 1920. Serial No. 434,249.

To all whom it may concern:

Be it known that HARRY A. FOOTHORAP, a citizen of the United States, residing at Harrisburg, in the county of Dauphin and 5 State of Pennsylvania, has invented certain new and useful Improvements in Date-Printing Mechanism for Writing Adding Machines, of which the following is a specification, reference being had therein to the accompanying drawing.

This invention relates to date printing mechanism for typewriting machines.

The object of the invention is to equip a typewriter, more particularly one of the flat 15 platen class, with a mechanism, distinct from the usual type arms, for printing a date or other data by a single stroke of the hand to save the time usually expended in the repetition of date writing or the typewriting of similar data which, in a particular 20 line of work, may call for frequent repetition.

To the accomplishment of this object, one embodiment of the invention resides in the 25 structure illustrated in the accompanying drawings, in which,

Figure 1 is a plan view of a flat platen typewriter equipped with my invention and having certain parts broken away.

Figure 2 is a side elevation of the machine.

Figure 3 is a front elevation with parts broken away and others in section.

Figure 4 is a detailed sectional view of the date printing mechanism.

Figure 5 is a plan view of the ribbon guide associated with the date printing mechanism.

The machine illustrated as equipped with 40 my invention, is what is known as an Elliott-Fisher machine. This machine includes a flat platen 1 traversed longitudinally by a line space frame 2 having front and rear guides 3 and 4 upon which travels transversely of the platen, a carriage 5. The carriage 5 is equipped with the usual printing mechanism including a type segment 6 upon which are grouped the type bars 7 operated from keys 8. The illustration of this type bar printing mechanism is fragmentary because it is well understood in the art and is broadly distinguishable for the present purpose as the primary printing mechanism of the machine. The usual ribbon spools 9 are 45 mounted at opposite ends of the carriage and from one to the other of these spools a ribbon 10 is suitably guided in a path which presents a portion of the ribbon at the common printing point 11 of the type bars.

In accordance with the present invention 60 an auxiliary printing mechanism separate and distinct from the usual type arms, or primary printing mechanism, is mounted at the left hand end of the machine as indicated at 12. This printing mechanism in 65 the illustrated embodiment is of ordinary construction, being the well known dating stamp, including printing wheels 13 having peripheral printing characters and the usual shank 14 which, in this instance, is pivotally 70 secured at its upper end, as indicated at 15, to the front end of what may be termed a supplemental or auxiliary key lever 16 extended across the end of the carriage. The lever 16 is pivoted at its rear end 17 and at 75 its front end is provided with a supplemental printing key 18 located at the front of the machine and adjacent to the key board. The front end of the lever 16 moves within a suitable guide 19.

Normally, the date printing mechanism assumes the elevated position shown in Figure 2, but may be presented to the work sheet by a blow upon the key 18 in an obvious manner. The date printing is designed 80 to be effected through the medium of the ribbon of the typewriter, as the inking medium, and for this reason the machine is equipped with the special ribbon guide 20 clearly shown in Figures 1 and 5. This 85 guide is preferably of metal and is formed with a printing aperture 21 directly above which the date printing mechanism is located. At opposite sides of the aperture 21 are formed slits 22 and 23 through which the 90 ribbon is threaded as it comes across the front of the machine, so as to present a section of the ribbon under the date printing mechanism and in position to serve as the inking means for the latter. From the slit 23 the ribbon 95 is led around opposite edges of the guide to return it to a position in line with the adjacent spool, to which it is guided as shown. By means of the guide 20 a portion of the 100 ribbon will be seen to have been carried beyond one end of the carriage to serve the date printing mechanism, without in any way affecting the normal feed of the ribbon 105 which constantly presents new portions of the latter in position for use.

While I have shown and described the auxiliary printing mechanism as a date printer, it must be understood that in the broader aspects of the invention the specific character of this printing mechanism and the character of data printed thereby are not material, and I therefore reserve the right to effect such modifications and variations of the illustrated structure as may be comprehended within the scope of the appended claims.

What I claim is:

1. The combination with a typewriting machine, including a movable carriage, type bars and inking ribbon, of a secondary printing mechanism including a key lever mounted at one end of the carriage, printing mechanism carried by the key lever; and an extension guide for the ribbon, said guide being located at the end of the carriage to guide the ribbon under the secondary printing mechanism and to support the ribbon at

points adjacent to the secondary printing mechanism and at opposite sides thereto.

2. The combination with a typewriting machine, including a movable carriage, type bars and an inking ribbon, of a secondary printing mechanism located beyond one end of the carriage and including a key lever and a printing device carried thereby, a pair of ribbon spools mounted within the length of the carriage, means for guiding the ribbon from said spools past the printing point of the type bars and an extension ribbon guide for guiding the ribbon beyond one end of the carriage in cooperative relation to the secondary printing mechanism.

In testimony whereof I hereunto affix my signature in the presence of two witnesses:

HARRY ARTHUR FOOTHORAP.

Witnesses:

J. AZALIA WIGFIELD,
MARSHALL H. DEAN.
